DISH RACK FOR DISHWASHING MACHINES

Ronald M. Kent, 10 Pinehurst Crescent, Toronto,
Ontario, Canada

Filed Aug. 29, 1960, Ser. No. 61,924

Term of patent 14 years

(Cl. D49—1)

The figure is a perspective view taken from the front and top of a dish rack for dishwashing machines, showing my new design.

I claim:

The ornamental design for a dish rack for dishwashing machines, as shown.
